Attorney

UNITED STATES PATENT OFFICE.

RICHARD L. LLOYD, OF MINNEAPOLIS, MINNESOTA.

GAME.

1,348,817.

Specification of Letters Patent.

Patented Aug. 3, 1920.

Application filed September 16, 1919. Serial No. 324,157.

To all whom it may concern:

Be it known that I, RICHARD L. LLOYD, a citizen of the United States, residing at Minneapolis, in the county of Hennepin and State of Minnesota, have invented certain new and useful Improvements in Games, and do hereby declare the following to be a full, clear, and exact description of the invention, such as will enable others skilled in the art to which it appertains to make and use the same.

This invention relates to amusement apparatus and more especially to that type of apparatus in which a game may be played wherein a suitable target set up in a field or on a playing surface is designed to be knocked from view or from the surface; such a game for instance being treated herein as characterizing nine or ten pins. It is obvious that the invention may be incorporated in various adaptations as may be desired without departing from its broad spirit.

Especially the present game consists of a pin or pins to be set up to be struck by a propelled device such as a ball and the invention consists in improvements for retaining the targets in the field or on the playing surface with a suitable and sufficient force and further provides means for accurately positioning the targets, said means being provided with other means acting in opposition to the means holding the targets set up so that when a target has been impinged by a projectile the released target is automatically withdrawn from the field.

It is an object of the present invention to improve the means for holding the target in the field; to improve the automatically removing means so as to eliminate unnecessary tension in the removing means after the target has been withdrawn from the field; and to improve the setting up means as will be more particularly described herein-after relative to the embodiment of the invention illustrated in the accompanying drawings, in which:

Figure 1 is a longitudinal sectional view of a type of the game involving targets of the character of ten-pins, and in which figure a plurality of the targets are shown in the field and certain of them withdrawn.

Fig. 2 shows a longitudinal section of a portion of the playing field with the setting up means in the setting up position.

Fig. 3 is a perspective view of one modification of the pin removing device, and

Fig. 4 is a side elevation of a modified or metallic spring form of the pin removing device.

As shown the game embodies a playing surface in the form of a plane which may comprise a floor or table 2 of suitable construction, dimensions and material over which there may be rolled a ball or balls to impinge upon and knock down one or another of a set of pins, the pins indicated at 3. A feature of the present invention resides in the provision of a permanent magnet suitably countersunk in the floor or surface 2 to facilitate the setting up of the pin or pins from a remote point. I have found that such a magnet for each pin can be effectively and economically produced by making the same of a substantially solid block of metal 4 of suitable dimensions and longitudinally slitting the same at 5 to form the negative and positive poles for the permanent magnets into which the block will be transformed when it is magnetized.

The lower end of each of the pins 3 is provided with an armature 6 so that when the pin is moved into juxtaposition with its respective magnet it is attracted and quite firmly held in the desired, and in the present case, vertical position.

A feature of this invention resides in the means for readily setting up any or all of the pins or targets that may have become detached from their respective positions and in this case I provide a movable, and what might be termed templet 7, in the form of a shelf or bridge mounted for movement by any suitable or appropriate mechanism indicated as including supports 8 appropriately mounted with respect to the table or floor 2 and which may be operated by any suitable lever mechanism or other means. This templet is shown as provided with a series of upwardly extending posts or brackets 10 which may be provided with threaded ends 11 to screw into the plate 7. The upper end of each bracket 10 is provided with a laterally extending arm 12 to receive a suitable connection in the form of a contractile member or device 13 which, in Fig. 3 is shown as comprising a piece of elastic material 14 such as rubber, the upper end of which is provided with an eye 15 to pass over the hook 12. The lower end of the element 13 or device 13 is provided with a head 16 to seat in a countersink 17 formed therefor, in this case, in the bottom face of the armature 6.

The templet 7 is provided with a series of apertures 7^a of a slightly less diameter than the major transverse diameter of the body of the pins 3 so that when the upper end of 5 the pins are inserted upwardly through the apertures 7^a the eyes 15 of the tension members 13 can be hooked over the hook-ends of the brackets 10, these ends alining with the center of the respective apertures 7^a. An 10 advantage of this construction is that when the platen is in the elevated position the tension device 13 will be placed under tension while the pins 3 are connected to the floor as by the magnets 4. Instantly the 15 pins are released by impact of the projectile, the tension members 13 withdraw the pins as the connection is broken, the released pin rising to a seat at the rim of its respective opening 7^a. When in this with- 20 drawn position all tension of the tension de- vices 13 is substantially relieved as the eye 15 is connected to the hook 12 at such position above the plate 7 as to just hold the pins against the plate.

25 In operation of the device the platen 7 is moved downwardly carrying with it the hooks to which the pins 3 are connected and in the lowermost position of the templet the pins are pressed onto the proper magnets 30 for holding them in the desired set-up position. Thereupon the platen is returned to its elevated position and the connecting de- vices 13 placed under sufficient tension to lift or remove the released pins, as they are 35 knocked from the magnets 4.

In Fig. 4 there is shown a modified form of the tension device in which it is made of a coiled spring 14^a of a strength determined of course by the weight of the pin. 40 By providing the head 16 on the tension devices it will be apparent that in the event of the breakage of any of the devices the same can be withdrawn readily from the aperture formed therefor axially in each of 45 the pins; the head of course preventing the elastic 14 or the spring 14^a from passing freely through and out at the upper end of the pin.

It will be seen that each of the magnets is 50 entirely independent of each other and that it is not necessary to provide any controlling switch or any source of electrical energy to secure an efficient, reliable, and very effective service of the magnetic system.

55 What I claim is:

1. In an amusement apparatus, a field, targets, and a carrier movable to and from the field, said carrier having a hole for each target of a diameter slightly less than the greatest transverse diameter of the target, 60 elastic elements connecting said targets to the carrier, and means for temporarily holding the targets on the field.

2. In an amusement apparatus, a field,

targets, and a carrier movable to and from the field, said carrier having a hole for each target of a diameter slightly less than the greatest transverse diameter of the target, brackets on the upper side of said carrier having hooks located over the centers of 70 said holes, elastic elements connecting said hooks with said targets through said holes, and means for holding said targets temporarily to the field.

3. In an amusement apparatus, a field, 75 targets, and a carrier movable to and from the field, said carrier having a hole for each target of a diameter slightly less than the greatest transverse diameter of the target, brackets on the upper side of said carrier 80 having hooks over the centers of said holes, elastic elements connecting said hooks with said targets, through said holes, and magnetic means for holding said target temporarily to the field.

4. In a game or other amusement apparatus, a target field having a series of magnets arranged with faces in a plane of the field, and targets each having an armature piece with a countersunk face, the said face 90 forming a seat for a removable tension member.

5. In an apparatus, having a field with magnetic means therein; and a set of targets each of which is provided with an 95 armature piece complementary to the magnets, said armature piece being countersunk; and a carrier for moving the targets toward the magnets and having elastic withdrawing means connecting the targets to the 10 carrier, said elastic withdrawing means each having a head countersunk in the said armatures.

6. In an apparatus, having a field with magnetic means therein; and a set of tar- 10 gets each of which is provided with an armature piece complementary to the magnets, said armature piece being counter- sunk; and a carrier for moving the targets toward the magnets and having elastic 11 withdrawing means connecting the targets to the carrier, said elastic withdrawing means each having a head countersunk in the said armatures, the said connecting means being removably mounted in the re- 1 respective targets and detachably connected to the carrier.

7. In an amusement apparatus, a field, targets, and a carrier movable to and from the field, said carrier having a hole for each 1 target of a diameter slightly less than the greatest transverse diameter of the target, means for elevating said targets from the field through the holes in said carrier, and means for temporarily holding the targets on the field.

In testimony whereof I affix my signature.

RICHARD L. LLOYD.
